UNITED STATES PATENT OFFICE.

ABRAM C. MOTT, JR., OF PHILADELPHIA, PENNSYLVANIA, ASSIGNOR TO ABRAM COX STOVE COMPANY, OF PHILADELPHIA, PENNSYLVANIA, A CORPORATION OF PENNSYLVANIA.

BOILER-FURNACE.

1,276,395.

Specification of Letters Patent. Patented Aug. 20, 1918.

Application filed September 8, 1917. Serial No. 190,341.

To all whom it may concern:

Be it known that I, ABRAM C. MOTT, Jr., a citizen of the United States, residing in Philadelphia, Pennsylvania, have invented 5 certain Improvements in Boiler-Furnaces, of which the following is a specification.

My invention relates to certain improvements in cast metal boilers used for heating buildings, either by hot water or steam.

10 The object of the invention is to simplify the construction of the boiler and thus reduce the cost of manufacture.

In the accompanying drawings:—

Figure 1, is a front elevation of my improved boiler;

Fig. 2, is a longitudinal sectional view on the line 2—2, Fig. 3;

Fig. 3, is a sectional elevation on the line 3—3, Fig. 1;

20 Fig. 4, is a sectional plan view on the line 4—4, Fig. 3;

Fig. 5, is a detached perspective view of the fire pot section of the boiler;

25 Fig. 6, is an inverted perspective view of the dome section;

Fig. 7, is a perspective view of a modification of the fire pot section;

Figs. 8 and 9, are sectional views illustrating an intermediate section; and

30 Fig. 10, is a plan view of an intermediate section.

Referring to the drawings, 1 is the base of the boiler structure made of cast iron and inclosing the ash pit 2. 3 is the grate made 35 in sections, as shown, and having its bearings in the base section. This grate can be of any suitable type. 4 is the fire pot section and 5 is the dome section. The fire pot section 4 is mounted on the base and the dome section is mounted upon and secured 40 to the fire pot section. The fire pot section is made hollow, as shown, forming an annular water space 6, which is connected to the water space 7 in the dome 5 through the 45 overhead passages 8 in two projections at the upper end of said fire pot section and through neck 9 in the dome section.

The hollow projections are made integral 50 with the fire pot section and extend over the fire, as shown in Fig. 2, and are connected to the base 10 of the dome section by nipples 11 in the manner common to this type of boiler. The base portion of the dome is of the same diameter as the top of the 55 fire pot section and the dome is contracted

to form the neck 9, leaving a channel 12 between the dome proper and the base 10 and this is inclosed by an annular plate 13 and forms a flue which connects at the forward end of the boiler with the combustion chamber and at the rear with a flue box 14 having a damper 15 therein. In the upper part 60 of the dome is an opening 16 to which is attached one of the circulating pipes and in the lower portion of the fire pot section is an opening 17 communicating with the water space to which the other circulating pipe is attached.

17 is a fire door frame, which extends from a point below the fire door opening 18 70 to the under side of the dome 5, and pivotally mounted on this frame is the fire door 20, which extends the full height, as shown in Fig. 1, so that when the door is open it not only exposes the fire chamber, but also 75 the flue 12, which surrounds the neck 9, and in the door is the usual damper 19. By this construction, the channel or flue 12 can be readily cleansed by simply opening the main fire door. In the base is the usual ash 80 pit door 22 and directly above the grate is the clean out door 21 of the ordinary type.

In Fig. 7, I have shown a single hollow projection 8^a located at the back of the boiler, as it will be understood that in boilers 85 of small size a single passage may be sufficient.

Thus it will be seen, by the above construction, that I make the boiler proper in two parts and form one or more passages 90 in the projecting portions of the fire pot section, which extend over the fire and are coupled to the base of the dome section, which is also exposed to the direct action of the fire, and between this base and the body 95 portion of the dome is a neck through which the water circulates, while the products of combustion pass around the neck from the fire chamber to the chimney stack.

In Figs. 8, 9 and 10, I have shown an 100 intermediate section 23 having, in the present instance, two openings in its bottom, forming communication with the fire pot section 4^a through nipples 11^a, and in the top of this intermediate section are two 105 openings alining with the openings in the dome section 5^a and the two sections are connected by nipples 11^b, as shown. The section is hollow and has a flue 24 therein connected at the rear with the combustion cham- 110

ber of the fire pot section and at the forward end with the flue 12^a in the dome section. This construction may be used when increased heating surface is desired.

5 I claim:—

1. The combination in a boiler, of a cast metal fire pot section having a water chamber therein; a cast metal dome section made hollow and forming a water chamber and 10 having a contracted neck and an extended base arranged to fit on the upper end of the fire pot section; an opening at one side of the fire pot section communicating with the water chamber of said section and an opening 15 in the dome section at one side of the center; and means for coupling the two sections together at the openings so that the water will circulate through both sections, leaving the bottom of the dome section exposed to 20 the products of combustion.

2. The combination in a boiler, of a cast metal fire pot section having a water chamber therein; a cast metal dome section made hollow and forming a water chamber and 25 having a contracted neck and an extended base, the base being arranged to fit the fire pot section; two openings in each section, one at each side of the center of the openings in the fire pot section communicating 30 with the water chamber therein and the openings in the dome section communicating with the water chamber therein; nipples in the openings connecting the two sections; and a plate inclosing the space surrounding 35 the neck of the dome section and communicating with the fire chamber, the base of the dome section being discontinued at one side to form a flue passage.

3. The combination in a boiler, of a fire 40 pot section made hollow and forming an annular water space surrounding the fire chamber and having two hollow portions projecting at the upper end toward each other and into the combustion chamber, each projection having an opening with a water section 45 mounted on the fire pot section and having openings alining with the openings in the hollow projecting portions; nipples connecting the two sections; and a passage in the 50 upper section communicating with the combustion chamber of the fire pot section to allow for the passage of the products of combustion to the chimney.

4. The combination in a boiler, of a cast 55 metal fire pot section and a cast metal section mounted on the fire pot section, each section having a water chamber therein; means for connecting the water chambers of the two sections, the upper section hav-

ing a contracted neck; a plate surrounding the neck and forming a flue, the lower portion of the upper section being reduced at the front to form a passage between the fire chamber of the fire pot section and the flue of the upper section; and a fire door frame extending from the point above the flue of the upper section to a point below the upper end of the fire pot section, forming an enlarged passage for the products of combustion; and a door closing said frame.

5. The combination in a boiler, of a fire pot section made hollow and forming an annular water chamber around a central fire chamber and having a hollow projection at the upper end extending over the fire chamber; each projection having an opening in the upper portion thereof; a dome section made hollow and having an enlarged main portion; a contracted neck and a base, said base fitting on the upper end of the fire pot section and having an opening therein alining with the projections in the fire pot section, the base of the dome section being discontinued at the front to form a passage between the fire pot section and the space surrounding the neck of the dome; a plate extending from the base of the dome and inclosing a flue space of the neck; and a flue box communicating with the space so that the products of combustion will pass from 90 the fire box around the neck of the dome.

6. The combination of a base; a fire pot section mounted on the base and having an annular water chamber therein; two projections, one at each side extending into the upper portion of the combustion chamber of the fire pot section and having openings in the upper portion thereof communicating with the annular water chamber; a fire door opening formed at the front of the fire pot section and between the two projections; a dome section having a reduced portion forming a neck and a base section of the same diameter as the upper portion of the fire pot section and having two openings therein arranged to aline with the openings in the fire pot section; nipples connecting the two sections at the openings, the base of the dome section being reduced at the front end in line with the fire door opening of the base; a fire door frame inclosing the fire door opening; and an annular plate surrounding the dome section at the neck and forming a flue communicating with the chimney.

In witness whereof I affix my signature.

ABRAM C. MOTT, JR.
